(57) **CLAIM**

I claim the ornamental design for a video game simulator cockpit, as shown and described.

DESCRIPTION

FIG. 1 is a perspective view of a video game simulator cockpit showing my new design;

FIG. 2 is a front view thereof

FIG. 3 is a left side view thereof

FIG. 4 is a right side view thereof

FIG. 5 is a rear view thereof

FIG. 6 is a top plan view thereof; and,

FIG. 7 is a bottom plan view thereof.
